H. POETTER.

GAS PRODUCER.

APPLICATION FILED NOV. 28, 1913.

1,097,141.

Patented May 19, 1914.

UNITED STATES PATENT OFFICE.

HEINRICH POETTER, OF DUSSELDORF, GERMANY.

GAS-PRODUCER.

1,097,141.

Specification of Letters Patent. Patented May 19, 1914.

Application filed November 28, 1913. Serial No. 803,373.

To all whom it may concern:

Be it known that I, HEINRICH POETTER, a subject of the King of Prussia, residing at 126 Grafenberger Allee, Dusseldorf, Germany, have invented certain new and useful Improvements in Gas-Producers, of which the following is a specification, reference being had to the accompanying drawings.

19 This application relates to improvements in gas producers, and more particularly to stirring devices for gas producers provided with rotary grates; and it has for its main object to provide improved means for stirring the fuel at the peripheral portion of the zone of distillation, so as to prevent the caking of this fuel and the consequent cavitation and burning away of the wall of the generator at this point which frequently arises when, as heretofore usual, the stirring device is arranged above the fuel, and operates mainly upon its central portion.

Other objects of the invention are to provide a stirring device that can be more effectually and economically water-cooled than heretofore, and that does not project into the depth of the gasification zone, and consequently becomes injured through burning.

Now in accordance with the present invention the stirring device is arranged in the zone of distillation that is to say, at the level of the fresh or green fuel, which is most liable to cake and to form masses of considerable size that adhere to the generator wall and thus interfere with the proper working of the generator; while the construction adopted is moreover such as to stir most vigorously that portion of the fuel which otherwise would be most likely to become caked and consequently prejudicially to influence the uniform working of the generator, that is to say, the portion close to the brickwork of the producer. In this construction the stoking arm is arranged in the wall of the generator in such manner as to exercise a leveling and distributing action on the fuel and by this means to obviate the formation of cavities in the charge, more particularly in proximity to the brickwork, and thus to secure a maximum yield of gas containing a minimum amount of carbon dioxid.

The invention is hereinafter more fully

described with reference to the accompanying drawings; wherein—

Figure 1 is a vertical half section through a gas producer provided with a stirring device according to the invention, on a plane containing the stirring devices; Fig. 2 is a partial vertical section on a different plane; and Fig. 3 is a partial horizontal section at the level of the stirring device.

Referring now to the drawings:—A water-cooled arm *a* attached to the wall of the generator projects through an aperture *a*₃ in the wall horizontally into the distillation zone thereof. The water-cooled arm *a* is mounted on a trunnion *a*' and provided with a circuit *a*₂ for cooling water supplied from any suitable source. On the trunnion *a*' there is keyed an arm *c* which can be rocked by means of an eccentric *d*. Between the rotary upper portion *b* of the generator and the remainder of the framework thereof there are provided water seals *i* and *k* with the result that the upper portion *b* and the lower portion comprising the grate *n* and the tank *o* can be independently rotated, or either may remain stationary while the other is rotated. The upper portion *b*, which is closed by a fixed top *b*' having mounted on it a fuel hopper *l* and a gas delivery pipe *m*, is furnished with a number of slightly conical guide wheels *h* arranged around its periphery, and running on a circular slightly conical track *g*, whereby a proper rolling movement between the parts *h*, *g* is obtained. The rotation of the upper portion *b* of the producer is effected by means of worm gear *e*, *e*' while the lower portion of the producer is carried by ball bearings *p* and rotated by worm gear *q*, *q*'. That guide wheel *h* which is situated beneath the stirring arm *a* is freely rotatable upon a shaft *f*' to which there is keyed a driving wheel *f* that meshes into a circular rack *g*' arranged concentric to track *g*. To shaft *f*' is also keyed the eccentric *d* by means of which the arm *c*, the trunnion *a*' and the stirring device *a* are rocked, this latter device consequently oscillating between its extreme positions indicated respectively by full and broken lines in Fig. 1.

The operation of the apparatus is as follows:—When the worm-wheel *e* is rotated, the upper portion *b* of the generator is also

caused to rotate, the consequent rotation of the driving wheel *f* resulting in the rotation of the eccentric *d* by the action of which the arm *c* is rocked and the stirring arm *a* oscillated between its upper and lower positions, respectively indicated in Fig. 1 by full and broken lines.

What I claim is:—

1. A gas producer having a rotary wall combined with a fuel-stirring device fastened to said wall and projecting laterally into the interior of the producer at approximately the distillation zone thereof, and means actuated upon a rotation of said wall for oscillating the stirring arm.
  2. A gas producer having a rotary wall provided with an aperture located at approximately the distillation zone of the producer, combined with a fuel stirring arm pivoted to said wall and extending through the wall-aperture, means for rotating the wall, and means actuated upon such rotation for oscillating the stirring arm.
  3. A gas producer having a rotary wall provided with an aperture located at approximately the distillation zone of the producer, combined with a hollow fuel stirring device pivoted to said wall and extending inwardly through the wall-aperture, means for rotating the wall, means actuated upon such rotation for oscillating the stirring arm substantially between a horizontal position and a downwardly inclined position, and means for admitting a cooling medium to the interior of the stirring device.
  4. A gas producer having a rotary wall provided with an aperture located at approximately the distillation zone of the producer, combined with a hollow fuel stirring arm extending inwardly through the wall aperture and having a hollow trunnion that communicates with the interior of said arm, means for rotating the wall, means actuated upon such rotation for oscillating the stirring arm, and a pipe for supplying a cooling medium to said trunnion.
  5. A gas producer comprising a lower portion and an upper portion rotatably mounted upon said lower portion, means for rotating the same, a fuel stirring device that is pivotally mounted on a horizontal axis supported on the exterior of the wall of said upper portion, that projects through an aperture in said wall into the distillation zone and is adapted to be oscillated between a horizontal and a downwardly inclined position, a circular track surrounding said upper portion, guide wheels adapted to travel on said track and rotatable around shafts carried by said upper portion, one of said guide wheels and shafts being located below said stirring device, a driving wheel keyed on shaft last mentioned, and adapted to run on said track, an eccentric likewise keyed on this shaft, an arm connected to and projecting from the axis of aforesaid stirring device, and an eccentric strip and rod whereby said eccentric is connected with said arm to actuate same and thereby to oscillate said stirring device.
- 70
6. A gas producer comprising a lower portion and an upper portion rotatably mounted upon said lower portion, means for rotating the same, a fuel stirring device that is pivotally mounted on a horizontal axis supported on the exterior of the wall of said upper portion, that projects through an aperture in said wall into the distillation zone and is adapted to be oscillated between a horizontal and a downwardly inclined position, a circular track surrounding said upper portion, guide wheels adapted to travel on said track and rotatable around shafts carried by said upper portion, one of said guide wheels and shafts being located below said stirring device, a driving wheel keyed on shaft last mentioned, and adapted to run on said track, an eccentric likewise keyed on this shaft, an arm connected to and projecting from the axis of aforesaid stirring device, and an eccentric strip and rod whereby said eccentric is connected with said arm to actuate same and thereby to oscillate said stirring device, a fixed top supporting a fuel hopper and a gas delivery pipe being moreover provided for said upper rotatable portion and water seals being also provided between said fixed top and upper producer portion, and also between said upper and lower producer portions.
